ATTORNEY

UNITED STATES PATENT OFFICE.

WALTER M. DANN, OF WILKINSBURG, PENNSYLVANIA, ASSIGNOR TO WESTINGHOUSE ELECTRIC & MANUFACTURING COMPANY, A CORPORATION OF PENNSYLVANIA.

TRANSFORMER RADIATOR.

Application filed March 14, 1921. Serial No. 452,357.

To all whom it may concern:

Be it known that I, WALTER M. DANN, a citizen of the United States, and a resident of Wilkinsburg, in the county of Allegheny and State of Pennsylvania, have invented a new and useful Improvement in Transformer Radiators, of which the following is a specification.

My invention relates to heat-dissipating devices and it has peculiar relation to apparatus of the above designated character that is particularly adapted for use in connection with electrical or other apparatus adapted to be immersed within a cooling fluid. More specifically, my invention relates to means for cooling the oil or other fluid used in transformers and to the construction of such means.

One object of my invention is to provide a radiator of novel type having a relatively large radiating area, as compared with the quantity of cooling fluid therein.

Another object of my invention is to provide radiators that shall be light in weight, simple and inexpensive in manufacture and of a type designed to withstand considerable stresses without deformation.

Briefly speaking, my invention comprises constructing the side walls, the top and bottom members and the end walls of separate members which are welded together after being assembled.

Heretofore, it has been customary to construct radiators of spaced tanks or headers and a plurality of spaced tubes disposed intermediate, and communicating with, said headers. The objection to such structures is that dead air spaces of substantially pyramidal shape are formed, of which the inner surfaces of the headers constitute the bases.

According to my invention, my radiator comprises a vertically extending central chamber having a plurality of offset chambers radiating therefrom. The offset portions are formed by the side walls which consists of a plurality of segments of substantially U-shape joined together in side-by-side relation. Each of the top and the bottom enclosing members of the central vertically-extending chamber is of substantially U-shape. The ends of the radiator are closed by separate end members welded to the ends

of the side walls and to the ends of the top and bottom members.

In the accompanying drawings, Figure 1 is a plan view of a radiator constructed in accordance with my invention.

Fig. 2 is a view, partially in end elevation and partially in section, of the structure shown in Fig. 1, the sectional portion of this figure being taken along the line II-II of Fig. 1.

Fig. 3 is a perspective view of certain of the members embodied in a radiator constructed in accordance with my invention.

According to my invention, a radiator comprises a top member 4 and a bottom member 5 joined together at the sides by walls 6 and 7 and at the ends by end members 8 and 9. Each of the members 4 and 5 consists of a pressed metal part of substantially U-shape which constitutes the top and the bottom, respectively, of a vertically-extending fluid chamber 10.

Each of the side walls 6 and 7 comprises a plurality of pressed-metal members 11 of substantially U-shape, as best shown in Fig. 3. For the sake of clearness, but two such members are shown on each side. Each of the members 11 consists of a base portion 12 and two integral side portions 13 of substantially dish-shape. The base portion 12 is welded at the top and at the bottom to the members 4 and 5, respectively. The edge of each of the side portions 13 is adapted to engage the edge of the side portion of the next adjacent member 11. This forms a flat metallic envelope having an open side which is in communication with the central chamber 10.

Each of the side members 13 is provided with extruded portions 14 to engage similar portions extending from the other integral portions 13 which constitutes one wall of the next adjacent fluid chamber. Distortion of the walls by the pressure of the fluid within the members 11 is thereby prevented. Each of the two coacting portions 13 of adjacent units 11, which co-operate to form a radiating chamber, is provided with an outwardly projecting flange 15 which is welded to a similar coacting flange 15 of the next adjacent portion 13.

Each of the end members 8 and 9 is of

substantially dish-shape and they co-operate with the end sections 16 of the members 11 to form, at each end of the radiator, a metallic envelope closed at both ends and open in the middle of one side.

Each of the members 8 and 9 is provided with a flange 17 of similar contour to the flange 18 of the member 16, to which it is welded. A plurality of extruded vertical ribs 19 serve to reinforce the end members 8 and 9. A plurality of tie-bolts 20, extending through the end members 8 and 9 and the vertical chamber 10, serves to support the entire radiator and to add to its rigidity and strength. Bracing members 21 are disposed at the ends of the bolts 20 to engage the end members 8 and 9. Each of the end members 8 and 9 is provided with offset integral projections 22 at the top and bottom thereof which serve as closures for the ends of the top and bottom members 4 and 5, respectively, and are provided with flanges 23 which are welded to said members.

The radiator may, if desired, be constructed by first assembling a series of units 11 in side-by-side relation and welding together their adjacent flanges 15. The end members 8 and 9 may then be welded to the end sections 16 of the assembled units, and the tie-bolts 20 and braces 21 be disposed in their proper operative positions. The top and the bottom members 4 and 5, respectively, may then be placed in position, being welded to the ends of the base portions 12 of the side members 11 and to the flanges 23 of the offset portions 22 of the end members 8 and 9.

The offset portions 22 of the member 8 are provided with apertures 24 by means of which communication is established with a tank or other container, not shown. The pipes associated with the apertures 24 also serve as supports for the radiator.

From the foregoing description, it will be apparent that I have produced a radiator of novel type, that is light in weight, simple and inexpensive in manufacture, and durable in operation. Also, it is apparent that, in a structure manufactured in accordance with my invention, a free circulation of air in a vertical direction between the various sections is facilitated by reason of the straight walls thereof.

I claim as my invention:

1. A radiator comprising side walls and top and bottom members each composed of pressed-metal members of substantially U-shape.

2. A radiator comprising a main chamber enclosed by spaced top and bottom members and two parallel side walls disposed intermediate said members and attached thereto, said side walls severally comprising a plurality of separate members of substantially U-shape disposed in side-by-side re-

lation the adjacent edges of which are welded together to form auxiliary chambers closed on three sides and communicating with said main chamber.

3. A radiator comprising two parallel side walls severally composed of members of substantially U-shape disposed in side-by-side relation, the outer edges of said members being bent outwardly to form flanges, the flanges of adjacent members being welded together to form an envelope closed on three sides, and top and bottom members for connecting the ends of said first members in spaced relation to form a main chamber communicating with the open side of said envelopes.

4. A radiator comprising side walls severally composed of a plurality of members of substantially U-shape disposed in side-by-side relation, end plates attached to the outermost of said members and a plurality of tie-rods extending through said end plates to reinforce the same.

5. A radiator comprising two spaced side walls severally composed of a plurality of members of substantially U-shape disposed in side-by-side relation and welded together at the adjacent edges, end plates disposed intermediate the ends of said members and connecting the same and a plurality of tie-rods extending through said end plates and through the chamber between said spaced side walls to reinforce said structure.

6. A radiator comprising spaced top and bottom members, side walls disposed intermediate and connected thereto, said side walls severally comprising a plurality of members of substantially U-shape disposed in side-by-side relation, the base portions of said members being attached at their ends to said top and bottom members and the side portions of said members being provided with outwardly projecting flanges to engage similar flanges on the next adjacent units and being welded thereto.

7. A radiator comprising spaced top and bottom members, side walls disposed intermediate and connected thereto, said side walls severally comprising a plurality of members of substantially U-shape disposed in side-by-side relation, the base portions of said members being attached at their ends to said top and bottom members and the side portions of said members being provided with outwardly projecting flanges to engage similar flanges on the next adjacent units and being welded thereto, end members disposed at the ends of said rows of members and welded to the edges thereof.

8. A radiator comprising spaced top and bottom members, side walls disposed intermediate and connected thereto, said side walls severally comprising a plurality of members of substantially U-shape disposed in side-by-side relation, the base portions

of said members being attached at their ends to said top and bottom members and the side portions of said members being provided with outwardly projecting flanges to engage similar flanges on the next adjacent units and being welded thereto, end members disposed at the ends of said rows of U-shape members and welded to the edges thereof, said end members being provided with offset portions that are welded to the ends of said top and bottom members.

In testimony whereof, I have hereunto subscribed my name this 7th day of March, 1921.

WALTER M. DANN.
